UNITED STATES PATENT OFFICE.

CARL MÜLLER, OF CHICAGO, ILLINOIS, ASSIGNOR TO MARDER, LUSE & CO.,
OF SAME PLACE.

DESIGN FOR A FONT OF PRINTING-TYPE.

SPECIFICATION forming part of Design No. 12,801, dated March 7, 1882.
Application filed August 16, 1881. Term of patent 14 years.

To all whom it may concern:

Be it known that I, CARL MÜLLER, a citizen of the United States, residing at Chicago, in the county of Cook and State of Illinois, have invented and produced a new and original Design for a Font of Printing-Type; and I do hereby declare that the following is a full, clear, and exact description thereof, which will enable others skilled in the art to which it applies to make and use the same, reference being had to the accompanying printed copies of the font of type, making a part of this specification.

My invention consists of a new design for a font of printing-type of script letters in a running style.

In my new design the capitals and the lower-case letters whose terminal lines may not readily be curved and extended in the direction to connect with the other letters composing a word are provided with lines extending forward, forming connecting-lines, and the other letters of the font, except initial and final letters, have their terminal lines curved and extended forward and upward, forming connecting-lines, as shown in the printed specimens. The initial "M" has both its commencing and its terminal lines looped and curved, as shown. The lower-case final letters *d, n, r, s, and t* are of peculiar form, differing from all others now in use. The

d and n have their terminal lines curved and extended downward, forward, upward, and backward. r has its terminal line curved and extended slightly upward, forward, downward, and backward. s has its terminal line looped and curved downward and upward, terminating below the loop, and t has the upper portion of the stem looped, the lower portion of the looped line forming a grace-line at the back of the letter, and its terminal line, starting at the back of the lower portion of the stem, is extended backward across the grace-line, thence forward, and curved downward and backward, terminating in front and near the lower portion of the stem.

What I claim as new, and desire to secure by Letters Patent, is—

The new design for a font of printing-type in which some of the letters are provided with connecting-lines and other letters have their terminal lines curved, forming connecting-lines, and having the initial and final letters formed as shown and described.

In testimony that I claim the foregoing as my own invention I affix my signature in presence of two witnesses.

CARL MÜLLER.
